MEANS FOR SEPARATING THE CONSTITUENTS OF GASEOUS MIXTURES

Arthur J. Fausek and Irving F. Fausek,
Clayton, Mo.

Application August 4, 1943, Serial No. 497,302

1 Claim. (Cl. 62—122)

1

This invention relates generally to an apparatus for separating the constituents of gaseous mixtures, and more specifically to a dephlegmator for such an apparatus wherein constituents of atmosphere are separated, the predominant object of the invention being to provide a dephlegmator which is of such improved construction and arrangement that it is capable of performing its intended function in an improved and more efficient manner than was possible with apparatus heretofore known.

Fig. 1 is a fragmentary, vertical section showing the improved dephlegmator structure of the present invention arranged at the lower portion of a column of a separating apparatus.

Fig. 2 is an enlarged, fragmentary, vertical section of a portion of the dephlegmator structure illustrated in Fig. 1.

Fig. 3 is a top plan view of one of the members shown in Fig. 2 for supporting and centering the injector tubes illustrated in that view.

Fig. 4 is an enlarged, fragmentary, vertical section of one of the liquefying tubes of the structure illustrated in Fig. 1.

Fig. 5 is a horizontal section taken on line 5—5 of Fig. 4.

In the drawing, wherein is shown for purposes of illustration, merely, one embodiment of the invention, C designates a column of a separating apparatus whose lower portion constitutes a dephlegmator 19 constructed and arranged in accordance with the present invention. The dephlegmator 19 includes an inner cylindrical shell 21 which is disposed throughout a major portion of its length centrally within the shell 20 of the column C, a lower portion of said inner shell projecting out of the lower end of the column shell 20 and being extended some distance below the bottom thereof. Arranged at the lower end of the shell 20 of the column C is a horizontal wall 22, said horizontal wall being provided with a centrally located opening through which the inner cylindrical shell 21 extends, and outer and inner annular flanges 22a and 22b of said horizontal wall being suitably secured to said outer and inner shells, respectively. Likewise, the lower end of the inner, cylindrical shell 21 is closed by a closure member 23 which is suitably secured thereto. The dephlegmator structure includes a receptacle 18 which is of annular formation and surrounds the inner cylindrical shell 21, a conductor 17 being in communication with the annular chamber 18' of said receptacle 18.

Located above the horizontal wall 22, here-

10 tofore mentioned, is another horizontal wall 24 which is provided with upwardly and downwardly extended annular, circumferential flanges 24' to which upper and lower portions of the shell 20 of the column C are secured by welding, or otherwise. In like manner upper and lower portions of the inner cylindrical shell 21 are secured by welding, or otherwise, to annular shoulders forming parts of said horizontal wall 24. The horizontal wall 24 is provided with a plurality of portions 25 of increased height which are located between the walls of the outer shell 20 and the inner shell 21, as shown in Fig. 1, and each of these portions 25 supports a pair of tubes 26 15 which extend upwardly from said portions of said horizontal wall a considerable distance. The portions 25 are spaced circumferentially with respect to the horizontal wall 24 and the tubes 26 supported thereby are arranged in a pair of 20 circular rows, one within the other. The openings of the lower extensions of the portions 25 of the horizontal wall 24 preferably have diameters slightly greater than the outer diameter of the tubes 26, and each portion 25 is provided with a pair of tapered seats 27 at its lower end which are aligned with the tubes 26 supported by said portion 25.

At their upper ends the tubes 26 are secured by welding, or otherwise, to the bottom wall of 30 a hollow head 28 which is made up of a lower portion 28a and an upper portion 28b, said portions 28a and 28b of said head being provided with circumferential flanges which are suitably secured together, and said portions being so 35 shaped as to provide the head with an enclosed fluid-tight and gas-tight chamber 29. The upper portions of the tubes 26 extend through openings formed through the bottom wall of the head 28 and communicate with the chamber 29 thereof. Additionally, the dephlegmator 19 includes a bank of inner tubes 30 which are disposed within the inner shell 21 and are secured by welding, or otherwise, to the horizontal wall 24 and the bottom wall of the head 28, said tubes 30 communicating at their upper ends with the 40 chamber 29 of the head 28 and having open lower ends which terminate at points located slightly below the horizontal wall 24. Supported by the head 28, and secured by welding, or otherwise, to the top and bottom walls thereof is a centrally located tube 31. The centrally located tube projects upwardly above the top wall of the head 28 into a cavity 32 provided by an upwardly projected extension 33 of said top wall of said head, and said centrally located tube terminates

at its lower end at a point located slightly above the horizontal wall 24.

Associated with the tubes 26 is a plurality of injection tubes 34 of less diameter, there being one of the injection tubes 34 associated with each of the tubes 26 and each injection tube 34 being extended upwardly into its associated tube 26. At their lower portions the injection tubes 34 extend through openings formed in wall portions of the receptacle 18 and communicate with the chamber 18' thereof, and each injection tube 34 has secured thereto a tapered and apertured centering member 35 which is arranged in seated relation with respect to the appropriate tapered seat 27 of the portion 25 of the horizontal wall 24 with which said tube 34 is associated. By employing the centering members 35 the walls of the portions of the injection tubes 34 that extend into the tubes 26 are maintained in their proper spaced relation with respect to corresponding wall portions of said tubes 26.

An extremely important feature of the present invention has to do with the construction and the interior arrangement of the tubes 26 of the dephlegmator 19. Each of these tubes 26 has formed in the wall thereof a plurality of channels 36 which extend longitudinally of the tube in a helical manner from the upper portion of the tube to the lower end thereof. Also, arranged within each tube 26 is an elongated baffle 37 of helical formation, the windings of which extend helically in the opposite direction to the direction of extension of the helically extended channels 36 of the tube. In other words, the channels 36 of the tubes 26 may rotate in a right-hand manner, while the windings of the baffle 37 may rotate in a left-hand manner. The helical baffle 37 of each tube 26 extends from the upper portion of the tube in which it is arranged downwardly to the top edge of the associated injection tube 34 by which it is supported, and the transverse dimension of said helical baffle is approximately the same as the interior diameter of the associated tube. The function of the helical baffles 37 is to cause atmosphere which passes upwardly through the tubes 26, as will be presently explained in more detail, to be forced outwardly by the helical curvatures of the baffles 37 into close contact with the cold walls of the tubes, so as to render more efficient the operation of separating the constituents of said atmosphere, while the function of the helical channels 36 is to provide definite channelways through which liquid rich in oxygen, which is separated from the atmosphere during its upward passage through the tubes 26, may flow downwardly of the tubes and out of the lower ends thereof with a minimum of interference from the upwardly moving atmosphere. Liquid which flows out of the lower ends of the tubes 26, as explained above, gathers in an annular chamber 38 which is defined by the horizontal walls 22 and 24, and by lower portions of the outer shell 20 and the inner shell 21, as shown in Fig. 1, and communicating with this chamber is a conductor 39.

In the operation of the improved dephlegmator, atmosphere is delivered by the conductor 17 to the receptacle 18 and this atmosphere passes upwardly from said receptacle through the injection tubes 34 and is discharged upwardly into the tubes 26. These tubes 26 are extremely cold, being surrounded by a body of liquid oxygen O, and therefore liquefaction of the atmosphere discharged into the tubes 26 by the injection tubes 34 is brought about within said tubes 26. As a

result of such liquefaction of the atmosphere passing upwardly through the tubes 26, liquid rich in oxygen collects on the inner faces of the tubes and flows downwardly of the tubes 26 and is discharged from the lower ends thereof into the annular chamber 38 with which the lower open ends of said tubes 26 communicate. The action of liquefying the atmosphere that passes upwardly through the tubes 26 is improved and enhanced because of the presence within said tubes of the helical baffles 37 which, because of their helical form, force the atmosphere outwardly against the cold walls of the tube and thereby subject substantially all of such atmosphere to the cooling effect of the cold walls of the tubes. Also, because the inner faces of the tubes 26 are provided with the helical channelways 36, definite channels or passageways are provided for the downwardly moving liquid rich in oxygen, through which channels said liquid may flow with the minimum of interference from the upwardly moving vaporous atmosphere.

The vapors which reach the upper ends of the tubes 26 are made up largely of impure nitrogen with a relatively small percentage of oxygen adhering thereto, and these vapors are discharged into the chamber 29 of the head 28 whence they move downwardly through the descending tubes 30 to the chamber provided in the lower portion of the inner shell 21 of the dephlegmator. The cold liquid and vapors that so gather in the chamber referred to are conducted therefrom by the conductor 41.

Likewise, the liquid rich in oxygen that gathers in the chamber 38 passes upwardly therefrom through the conductor 39 to the upper portion of the column C, said liquid moving downwardly through the upper portion of the column and eventually passing into the trap 32 at the top 40 of the head 28 of the dephlegmator 19 wherein said liquid overflows into the tube 31 and is discharged into the chamber provided by the inner shell 21 and the horizontal wall 24. This liquid, which is substantially pure oxygen, builds up in the chamber referred to until it overflows the top of the inner shell 21 and fills the chamber between the inner and outer shells 20 and 21 to the approximate level of the top of the inner shell to provide a body of oxygen O as indicated in Fig. 1. Also, liquid moving downwardly from the upper portion of the column C passes around the head 28 into the chamber provided by the lower portion of the outer shell 20 and the horizontal wall 24.

The body of liquid oxygen O at the dephlegmator 19 is substantially pure oxygen and this oxygen is conducted away from the column C by the pipe 75b. It is to be noted that a pipe 75a is tapped into the column C at a point located slightly above the level of the body of liquid O at the dephlegmator 19 while the pipe 75b is tapped into said column at a point located some distance below said liquid level. Because of this arrangement either liquid oxygen or gaseous oxygen may be drawn from the column.

We claim:

An apparatus for separating atmosphere into its constituents which comprises a dephlegmator wherein a constituent of atmosphere is liquefied and separated from the remaining constituents of the atmosphere, said dephlegmator including a vertical liquefying tube, the wall of which is maintained in a cold condition and which is adapted for passage therethrough of atmosphere being acted on by the apparatus,

a helical baffle disposed within said liquefying tube and adapted to cause atmosphere passing through said tube to move in contact with the wall thereof, and a helical channelway formed in the wall of said liquefying tube at the inner face thereof which provides a passageway for liquid separated from atmosphere passing through said liquefying tube, the turns of said helical baffle and the turns of said helical channelway being extended helically in opposite directions. 10
